UNITED STATES PATENT OFFICE.

CHARLES WILLIAM McDANIEL, OF PORTSMOUTH, NEW HAMPSHIRE.

WRENCH MECHANISM.

Application filed November 8, 1924. Serial No. 748,569.

This invention is applicable to three types of wrench, viz., a socket wrench adapted to receive a polygonal nut, a plug wrench adapted to enter a polygonal socket in a screw-threaded plug, and a pipe wrench adapted to engage and rotate a cylindrical object.

The object is to provide a wrench mechanism or outfit from which the owner can provide himself with either of two duplex wrenches, one adapted to serve either as a socket wrench, or as a plug wrench, and the other to serve either as a plug wrench or as a pipe wrench.

The wrench mechanism above mentioned includes three elements, one of which is a stock having a fixed wrench jaw, while the others are movable jaws, adapted to be used interchangeably with the stock, one of the movable jaws and the stock constituting a duplex wrench, adapted to engage either the external surface of a nut, or the internal surface of a plug-socket, while the other movable jaw and the socket constitute a duplex wrench, adapted to engage either the internal surface of a plug socket, or the periphery of a cylindrical pipe.

Of the accompanying drawings forming a part of this specification,—

Figures 1, 2 and 3 show, in perspective, the component parts or elements of a wrench mechanism embodying the invention, Figure 1 showing the stock and its fixed jaw and worm, Figure 2, the movable jaw, used in a socket and plug wrench, and Figure 3, the serrated movable jaw, used in a plug and pipe wrench.

Figure 4 is a side view, showing two of the elements assembled to form a socket and plug wrench.

Figure 5 is an end view of the jaws shown by Figure 4, showing the jaws engaged with a hexagonal nut, as in a socket wrench.

Figure 6 is a side view, showing the stock and the serrated movable jaw, assembled to form a plug and pipe wrench.

Figure 7 is a section on line 7—7 of Figure 6.

Figure 8 is a section on line 8—8 of Figure 6, omitting the pipe.

Figure 9 is an end view, showing a wrench organized as shown by Figure 6, with its jaws in their socket-engaging ad-

justment, a plug having a socket engaged by the jaws being shown by dotted lines.

Figure 10 is a longitudinal section of the stock shown by Figure 1.

Figure 11 is a section on line 11—11 of Figure 1.

The same reference characters indicate the same parts in all, of the figures.

The stock element of my improved wrench mechanism is of oblong form, and has a fixed jaw 12, a worm-receiving opening 13, and a rack guide formed by a slot 14 (Figures 1 and 10) formed in one side of the stock, and spaced apart flanges 15, the inner surfaces of which are continuations of portions of the slot 14.

The stock also has a worm 16, mounted to rotate in the opening 13, on a stud 17, engaged with the stock, in the manner best shown by Figure 10. The fixed jaw 12 is preferably cast integral with the body portion of the stock and overhangs one end of said body portion. The fixed jaw has a reentrant inner cheek 18, adapted to conform to a portion of a nut 19, (Figure 5) and a salient outer cheek 20, adapted to conform to a portion of a socket 21 (Figure 9) in an externally threaded plug 22, shown in Figure 9 by dotted lines.

The stock in the condition shown by Figure 1, is adapted to cooperate with either of the movable jaws shown by Figures 2 and 3.

The movable jaw 23, shown by Figure 2, has inner and outer faces 18^a and 20^a, corresponding to the faces 18 and 20, so that this movable jaw and the fixed jaw are adapted to cooperate either in engaging a nut 19, or a plug 22.

The movable jaw 24, shown by Figure 3, has an inclined inner cheek, formed by a series of teeth 25, adapted to engage one side of a pipe 26, and a salient outer cheek 20^b, corresponding to the salient cheek 20 of the fixed jaw, so that this movable jaw and the fixed jaw are adapted to cooperate either in engaging a pipe, as shown by Figures 6 and 7, or a socket 21, as shown by Figure 9.

Each movable jaw is provided at its inner end with a post 26, formed to slide endwise without turning in the guide 14, and arranged at right angles with the jaw. On

the post are formed rack teeth 27, adapted to engage the worm 16, as shown by Figures 4, 6 and 8, the post being, therefore, a rack.

The rack of the serrated jaw, shown by Figure 3, is preferably longer than that of the jaw shown by Figure 2.

The rack 26 of either movable jaw may be engaged with the stock by inserting the rack in the guide 14, until one of its teeth 10 is in position to be engaged by the worm, and then turning the worm in the direction required to move the rack into the stock and the movable jaw toward the fixed jaw. The movable jaw may be left at any desired distance from the fixed jaw.

When the jaws are suitably adjusted, they may be locked against accidental movement by a detent composed of a screw-threaded shank 28 (Figure 8), engaged 20 with a tapped socket 29, in the stock, and a head 30, adapted to frictionally engage the worm; when the screw is turned outward from the position shown by Figure 8. The movable jaw may be ejected from the 25 stock by turning the rack in the direction required to move the rack out of the guide.

It will now be seen that either of the wrenches shown by Figures 4 and 6, may be conveniently and quickly provided by the 30 owner of the mechanism, the latter being adapted to be stored in small compass, or compactly in a tool-box.

The shank of the stock has a tapered end portion 31, polygonal in cross section and 35 provided at its inner end with a shoulder 32. 33 designates a handle having a tapered socket 34, formed to receive the end portion 31, and a resilient hooked tongue 35, secured to the head within the socket by 40 a rivet 36, and projecting from the larger end of the socket, the tongue being adapted to yieldingly engage the shoulder 32, and thus separably confine the socket and handle on the shank. The handle is quickly 45 removable by the application of force thereto, sufficient to disengage the hooked tongue from the shoulder, no tool being required.

When the handle is removed, the end portion 31 may be engaged by the chuck jaws of an ordinary bit brace, so that the stock may be rotated on its longitudinal axis more rapidly and forcibly than by the handle 33. The stock having the end portion 31, may constitute an element of any wrench having jaws, the cheeks of which are at opposite sides of the longitudinal axis of the stock, so that the stock and jaws

are coaxial, and may be rotated either by the handle, or by a bit brace.

60

I claim:

1. A wrench mechanism including the essential elements of three types of wrench, namely, a socket wrench adapted to receive a polygonal nut, a plug wrench adapted to enter a polygonal socket in a screw-threaded plug, and a pipe wrench adapted to engage and rotate a cylindrical object, said mechanism comprising a stock having a fixed jaw provided with a worm-receiving opening, and a rack guide communicating with said opening; a worm journaled in the stock opening, said rack guide adapted to receive two interchangeable movable jaws, each having a rack formed to engage the worm and movable into and out of the guide by rotation of the worm, so that the rack may be moved to various positions in the guide, and ejected therefrom, by rotation of the worm, the fixed jaw being provided with a 75 nut-engaging inner cheek and a socket-engaging outer cheek, while each movable jaw is provided with a socket-engaging outer cheek, one movable jaw being provided with a nut-engaging inner cheek, 85 while the other movable jaw is provided with a serrated pipe-engaging inner cheek, the stock, the worm, and one of the movable jaws being adapted to constitute a duplex wrench, adapted to turn either a nut 90 or a socketed plug, while the stock, the worm, and the other movable jaw are adapted to constitute a duplex wrench, adapted to turn either a pipe or a socketed plug.

2. A wrench comprising an elongated 95 stock having at its outer end a jaw fixed to the stock and a complementary jaw movably engaged with the stock; means carried by the stock and movable jaw for adjusting the latter, said jaws having cheeks at opposite sides of the longitudinal axis of the stock, the said stock having a tapered end portion polygonal in cross section and a shoulder thereon; and a handle having a tapered socket conforming to the tapered 100 end portion of the stock, and a resilient hooked tongue secured to the socket and projecting from the larger end thereof, and adapted to yieldingly engage said shoulder and separably confine the handle on the 105 stock, said tapered end portion being adapted to be engaged by a bit brace when the handle is removed.

In testimony whereof I have affixed my signature.

CHARLES WILLIAM McDANIEL.
